UNITED STATES PATENT OFFICE.

LUTHER L. KNOX, OF AVALON, PENNSYLVANIA, ASSIGNOR TO KNOX PRESSED & WELDED STEEL COMPANY, OF PITTSBURGH, PENNSYLVANIA, A CORPORATION OF PENNSYLVANIA.

ANNEALING-BOX.

1,187,066.

Specification of Letters Patent. Patented June 13, 1916.

Application filed April 17, 1915. Serial No. 22,079.

To all whom it may concern:

Be it known that I, LUTHER L. KNOX, a citizen of the United States, residing at Avalon, in the county of Allegheny and State of Pennsylvania, have invented a new and useful Improvement in Annealing-Boxes, of which the following is a full, clear, and exact description, reference being had to the accompanying drawings, forming part of this specification, in which—

Figure 1 is a top plan view partly broken away of an annealing box embodying my invention; Fig. 2 is a front elevation; Fig. 3 is a transverse section; Fig. 4 is a plan view showing one form of blank which may be employed in making the box, the successive steps of the drawing operation being indicated in dotted lines; and Fig. 5 is a sectional view of the blank and also indicating in dotted lines the successive drawing steps.

My invention has relation to annealing boxes, and is designed to provide a one-piece sheet metal annealing box which is entirely free from seams and joints. Also to provide a box of this character in which provision is made for expansion and contraction movements. My invention also provides a light and durable box.

In the accompanying drawings, in which I have shown the preferred form of box embodying my invention, the numeral 2 designates the body of the box which is open at the bottom; and 3 the integral arched top. The box is, in general, of the usual oblong form, but is provided at each of its corner portions with an outward swell or bend 4, extending beyond the general planes of the sides and ends of the box.

5 designates lifting lugs which are secured preferably by welding to opposite sides of the box.

The box is made from a single integral sheet of metal by successive drawing operations. I preferably start with a blank 6 of the general form shown in Fig. 4. In the first drawing or shaping step, the box is given the general oval shallow form indicated at 7 in dotted lines in Figs. 4 and 5. In the next forming step, it is given the deeper and generally oblong rectangular form shown at 8, in said figures. In the next step, the sides and ends of the box are

compressed, and the outwardly bulged corner portions 4 are formed.

It will be noted by reference to Fig. 4 55 that those portions of the blank which are to form the corner portions of the finished box are cut away, as indicated at 9 in Fig. 4, so as to prevent excess of metal at the corners. The upward bulges or swells at the corners 60 provide more or less flexible portions which will take up the expansion and contraction of the box in use, and prevent its giving way as a result of strains due to expansion and contraction. The bulges also permit the box 65 to be more readily placed in position over a pile of plates or sheets. The bulged corner portions also provide for taking up the excess of metal at the corners, as otherwise in forming a box with corners from a single 70 plate or sheet, the metal would necessarily be lapped or folded at the corners.

My invention provides a one-piece box which is entirely free from joints and seams and which is much lighter and less likely to 75 become broken or cracked in service than the usual cast box. There are no rivets or other weak points to give way in service, and all sharp corners or angles are avoided. I do not, however, limit myself to the exact 80 form of box which I have shown and described, as this may be changed, without departing from the spirit of my invention as set forth in the appended claims.

I claim:

1. An integral one-piece annealing box of generally rectangular form, die-formed to shape without joints or seams from a single piece of wrought metal, the excess metal at the corners being formed into outward 90 swells or bulges, substantially as described.

2. An integral one-piece annealing box of generally rectangular form, die formed to shape without joints or seams from a single piece of wrought metal, the excess metal at 95 the corners being formed into outward swells or bulges, the corner bulges merging into the smooth top, substantially as described.

3. An integral one-piece annealing box of 100 generally rectangular form, die formed to shape without joints or seams from a single piece of wrought metal, the excess metal at the corners being formed into outward

swells or bulges, and lifting lugs welded to the side walls of said box, substantially as described.

4. An integral one-piece annealing box of generally rectangular form, die formed to shape without joints or seams from a single piece of wrought metal, the excess metal at the corners being formed into outward swells or bulges, and lifting lugs welded to the side

walls of said box between the corner bulges, if substantially as described.

In testimony whereof, I have hereunto set my hand.

LUTHER L. KNOX.
